CLAIM

The ornamental design for an atomization device, as shown and described.

DESCRIPTION

FIG. 1 is a front, top, right perspective view of an atomization device, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, bottom, left perspective view thereof.

The dashed broken lines in the drawing depict portions of the atomization device that form no part of the claimed design.

The dot-dot-dash lines represent boundaries. The dot-dot-dash lines and anything shown outside the dot-dot-dash lines form no part of the claimed design.

1 Claim, 8 Drawing Sheets
